(57) **CLAIM**

The ornamental design of a popping toy cell as shown and described.

DESCRIPTION

FIG. 1 is a front, left, top perspective view of a popping toy cell in accordance with the present invention;

FIG. 2 is a top view thereof;

FIG. 3 is a bottom view thereof;

FIG. 4 is a front view thereof where the back, left and right views are identical;

FIG. 5 is a front, left, top perspective view of another embodiment of a popping toy cell in accordance with the present invention;

FIG. 6 is a top view thereof;

FIG. 7 is a bottom view thereof; and,

FIG. 8 is a front view thereof where the back, left and right views are identical.

The broken lines showing the remainder of the popping toy in FIGS. 1, 2, 5 and 6 are directed to environment. None of the broken lines form any part of the claimed design.

1 Claim, 4 Drawing Sheets
